CLAIM

The ornamental design for a combined support for finger rings and price display holder, as shown.

DESCRIPTION

FIG. 1 is a top front perspective view of a combined support for finger rings and price display holder, showing my new design;

FIG. 2 is a top rear perspective view thereof; FIG. 3 is a side elevational view taken from the right of FIG. 1;

FIG. 4 is a top plan view thereof;

FIG. 5 is a rear elevational view thereof;

FIG. 6 is a front elevational view thereof; and

FIG. 7 is a bottom plan view thereof.
